UNITED STATES PATENT OFFICE

CLIFTON K. RAINY, OF KNOXVILLE, TENNESSEE

TYPEWRITER-ESCAPEMENT MECHANISM

Application filed July 19, 1927. Serial No. 206,913.

This invention relates to a carriage escapement mechanism for typewriting, tabulating and other forms of recording machines.

The primary object of the invention is to provide an improved escapement of rotary type which permits a swift and uninterrupted movement of the carriage incident to the successive formation of the letters or characters.

Another object is to provide a rotary escapement mechanism of such construction as to positively stop the carriage at the completion of one letter or character space, thus obviating the possibility of the carriage moving more than one space during the single operation of a key lever.

Still another object is to provide an escapement mechanism which allows the carriage to move on each feed step without resistance inhibiting its rapid feed movement, and smoothly or without tremors or breaks such as are caused, for example, in feed mechanisms of double dog type incident to the transitional movement of a tooth of the escapement wheel from dog to dog, or to single dog escapement mechanisms in which there is a period of dwell in the escapement action.

Still another object of the invention is to provide a construction in which the entire releasing step occurs during the movement of a type bar in one direction, preferably on the return movement of said bar, so that the carriage will be held absolutely firm and stationary during the ensuing printing motion of the same or another type bar.

Heretofore the desired feed movement of the carriage has been generally attained in machines in use by means of the ordinary escapement wheel and a rocker arm carrying one or two dogs fixed or pivoted, which reciprocate across the path of the escapement wheel and alternately stop and release the same and consequently the carriage connected therewith. In these forms of escapement the shock incident to the stopping of the carriage at each letter space is delivered upon either a single dog or one of a pair, and such excessive use of these parts causes them to be quickly worn and their action inaccurate be-

cause of the disturbing of their delicate adjustment.

The present invention contemplates a broad departure from the old rocker motion and the use of a rotary spacing element carrying a plurality of dogs slidably movable when in working position upon the operation of a key to permit the escape of one tooth of the escapement wheel. Any number of these dogs may be employed upon the rotary spacing element, among which the wear is distributed so that the life of this portion of the machine is proportionately increased. These dogs are mounted so as to permit the escapement wheel to feed without spring resistance therefrom during a feed motion, and without break or interruption in its feed motion, whereby the speed of the escapement motion is greatly increased.

In the accompanying drawings illustrating the invention,—

Figure 1 is a rear elevation of the frame of a typewriter, showing the application of my invention thereto, parts of the universal bar mounting being omitted for sake of clearness of illustration.

Figure 2 is a vertical front-to-rear section through the machine showing only such parts as are necessary to a disclosure of the invention.

Figure 3 is a sectional view similar to Figure 2 through the escapement mechanism, such section being taken on line 3—3 of Figure 4.

Figure 4 is a sectional plan view of the spacing wheel and associated parts of the escapement mechanism.

Figure 5 is a view in end elevation of the spacing wheel and its feed ratchet.

Figure 6 is a section on line 6—6 of Figure 5.

Figure 7 is a perspective view of the supporting bracket and the parts of the universal bar mounted thereon.

Figure 8 is a perspective view of one of the feed dogs.

Referring to the drawings, 1 represents the top plate of the stationary frame of a typewriter, and 2 the shaft carrying the usual escapement wheel 3. The escapement wheel

is controlled by a spacing wheel 4, mounted upon a shaft 5, which also carries the spacing wheel feed ratchet 6. The shaft 5 is fitted to turn upon adjustable bearing members 7 mounted in a supporting bracket 8 secured to the underside of the top plate of the machine, said shaft 5 being arranged transversely of the machine so that the spacing wheel 4 and its ratchet 6 turn in a direction at right angles to the direction of rotation of the escapement wheel 3.

The feed wheel 4 is provided at opposite sides of its periphery with circumferential flanges 9, forming an intervening annular channel, in which are arranged an annular series of radially projecting dogs 10, each dog 10 being mounted upon a flat body portion, bar or shank 11 mounted to slide across the circumference of the wheel and through alined guide openings 12 in the flanges 9. These dogs are normally arranged in working position at one side of the circumferential center of the channel in the spacing wheel, and said dogs are adapted to successively engage and release one tooth of the escapement wheel 3 upon each operation of a key lever 13 of the set of key levers of the machine, one of which is shown in connection with a type bar 14 actuated thereby. As shown particularly in Figures 1, 4 and 6, the dogs 10 normally abut against the flange 9 facing the left hand side of the machine, as viewed from the front of the machine, and each dog is movable across the channel of the feed wheel and into engagement with the flange 9 at the right hand side of the channel for escapement wheel spacing, stopping and releasing actions. Figure 1 shows one of the dogs which has been shifted by a tooth of the escapement wheel to stop position, whereby the escapement wheel and carriage are firmly held from feed movement. When the spacing wheel is turned a distance of a dog for the next feed action, the dog which is in stopping position moves out of engagement with the tooth of the wheel 3 which it engages and the following dog comes into alinement with the next adjacent tooth of the escapement wheel and is shifted thereby laterally of the face of the wheel into stopping position, permitting the escapement wheel to turn a distance of one tooth for a letter or character space feed action.

Arranged at that side of the feed wheel toward which the dogs move for an escapement action is a controlling cam 15 which is fixed from rotation and suitably secured to and supported from the bracket 8. This cam 60 extends entirely around the adjacent side of the spacing wheel concentric with the shaft 5 and bears against the side of said wheel except at one point where it is provided with an offset portion 16. The body portion of this cam lying in contact with the side of the

feed wheel is thus arranged to provide a retracting and locking portion to engage the adjacent ends of the bars or shanks 11 and hold the dogs in normal position until, through the rotation of the spacing wheel, 70 the dogs come into alinement with the teeth of the escapement wheel, at which point the offset portion 16 is arranged so as to permit shifting of the dogs to the stop position and upon a releasing action to return each dog 75 to normal position in which it is locked by the body portion. By the construction described it will be seen that the dogs are normally retained against that flange 9 of the spacing wheel located adjacent the advancing 80 tooth of the escapement wheel by the body portion of the cam, and that a dog in position to be moved forward for an escapement action is brought into alinement with the advancing tooth of the escapement wheel by a 85 feed movement of the feed wheel, at which time the dog so fed up comes opposite the cam portion of the cam member, allowing said dog to be slid across the face of the spacing wheel in the direction of said cam member to permit the escapement wheel to turn the distance of one tooth and to then lock the escapement wheel against further movement and until the spacing wheel is again turned. In this escapement action it will be obvious 90 that the feed movement of the escapement wheel is continuous or without break or interruption, and without material resistance, since the controlling dog is freely slidable across the face of the spacing wheel, whereby a rapid escapement action free from jerks, jars or tremors is obtained.

The spacing wheel feed ratchet 6 is intermittently operated by a spring-pressed push pawl 17 mounted upon an arm 18 of the universal bar 19 which may be of usual construction and operated in one direction by the type bars 14 to shift the dog or pawl 17 rearwardly to starting position for a feed motion, and the bar 19 may be operated in 100 the opposite direction on its feed motion by a spring or springs 20, in which direction of movement the dog or pawl 17 engages and turns the ratchet wheel 6 a distance of one tooth for a corresponding feed motion of 110 the feed wheel. An adjustable stop 21 is provided for limiting the backward movement of the universal bar 19 under the action of the type bars 20, and a suitable stop 22 is provided for limiting the upward movement of the nose of the pawl 17 so that on the return movement of the universal bar 19 the pawl will positively engage a tooth of the wheel 6 and turn said wheel and so that at the end of such movement of the bar 19 the pawl will lock the spacing wheel against movement. It will be observed that the action is such that the feed ratchet and spacing wheel will be operated for an escapement action solely in one direction of mo- 120 125 130

tion of a type bar 14, which may be, if desired, in the direction of its printing motion, in which event the escapement mechanism, will, of course, act to allow the carriage to have feed motion and lock it against movement before the type bar moves to full printing position. I prefer, however, to employ the arrangement shown in the present instance, in which the action is such that the feed motion occurs solely and wholly during the return movement of a printing bar between its printing position and normal or retracted position, so that during the printing motion of the bar the carriage will be firmly held against motion while the printing action is taking place. The universal bar 19 may be operatively mounted upon the supporting bracket 8, as shown in Figure 7, in which a known type of construction is shown with the exception of the provision of the arm 18 and the push type of ratchet feed pawl 17. The improved escapement mechanism may otherwise be used in connection with the universal bar and escapement wheel of any conventional typewriter escapement mechanism, by the substitution of my improved rotary spacing wheel and coacting parts for the reciprocating dogs commonly employed.

The advantages of my construction are obvious. The rotary spacing wheel, provided with a large number of dogs, upon which the wear is equally distributed, reduces wear and tear upon the dogs of the escapement mechanism, thus overcoming the objections to escapement movements in which a single reciprocatory dog or a pair of reciprocatory dogs are employed for the purpose. Springs for controlling the dogs are entirely dispensed with, so that upon engagement of a tooth of the escapement wheel with a dog for an escapement action, no resistance to the movement of the escapement wheel or carriage is set up, thus enabling a quick escapement motion to be obtained. Rapidity of action, without irregularities of motion, are also secured to the highest degree by the provision of a single movement escapement action, in which the tooth of the escapement wheel engages but a single dog which moves in a single direction only to permit the escapement wheel to turn for the carriage feed movement. A strong and durable type of escapement mechanism is thus provided which is much less liable to get out of order than those of the type heretofore used, and which at the same time permits of a faster and smoother escapement motion of the escapement mechanism and feed motion of the carriage. It is well known that irregularities of alinement in the writing action are caused by irregularities of action of escapements of reciprocatory dog type in common use. My invention overcomes this objection, as my improved escapement mechanism permits the

escapement mechanism to operate for a carriage feed motion as fast as the typing mechanism can be either manually or mechanically operated.

As shown, the bars or shanks 11 and their guide openings 12 are of angular or non-circular form, whereby the dogs are held from tilting and are accurately guided so that a smooth and easily sliding motion is obtained and the dogs supported firmly whereby the dogs when adjusted to stop position will hold the escapement and carriage securely and solidly against movement. Since the dogs are moved from stop to initial position by means independent of the carriage, and are free to be moved by the escapement wheel in the opposite direction without the necessity of overcoming the resistance of springs or other devices, an exceedingly rapid escapement action is obtained and one in which, at the same time, does not cause irregular spacing of written letters or characters.

Having thus fully described my invention, I claim:

1. In a spacing mechanism for typewriting and like machines, an escapement wheel, an intermittently operable spacing wheel mounted to rotate on an axis arranged transversely of the machine, dogs slidable transversely of the face of the spacing wheel and adapted to be successively brought by the rotation of the spacing wheel into and out of the path of successive teeth of the escapement wheel and to be shifted by the teeth of the latter laterally on said spacing wheel to stop position, and means for maintaining said dogs in initial position and releasing them for shifting motion to stop position and thereafter returning them to initial position.

2. In a spacing mechanism, an escapement wheel, an intermittently operable spacing wheel, slidable dogs on the spacing wheel adapted to be successively brought by the rotation of the spacing wheel into and out of the path of successive teeth of the escapement wheel and to be shifted by the teeth of the latter laterally on said spacing wheel to stop position, and controlling means mounted independently of the wheel for maintaining said dogs in initial position and releasing them for shifting motion to stop position and thereafter returning them to initial position.

3. In a spacing mechanism, an escapement wheel, an intermittently operable spacing wheel, slidable dogs on the spacing wheel adapted to be successively brought by the rotation of the spacing wheel into and out of the path of successive teeth of the escapement wheel and to be shifted by the teeth of the latter laterally on said spacing wheel to stop position, and a cam device for maintaining said dogs in initial position and releasing them

for shifting motion to stop position and thereafter returning them to initial position.

4. In a spacing mechanism, an escapement wheel, an intermittently operable spacing wheel, slideable dogs on the spacing wheel adapted to be successively brought by the rotation of the spacing wheel into and out of the path of successive teeth of the escapement wheel and to be shifted by the teeth of the latter laterally on said spacing wheel to stop position, and a stationary cam device supported independently of the spacing wheel and operative for maintaining said dogs in initial position and releasing them for shifting motion to stop position and thereafter returning them to initial position.

5. In a spacing mechanism, an escapement wheel, an intermittently operable spacing wheel, slideable dogs on the spacing wheel adapted to be successively brought by the rotation of the spacing wheel into and out of the path of successive teeth of the escapement wheel and to be shifted by the teeth of the latter laterally on said spacing wheel to stop position, means for maintaining said dogs in initial position and releasing them for shifting motion to stop position and thereafter returning them to initial position, and key lever actuated ratchet means operative during the retraction of the key lever after a printing action for turning the spacing wheel for a spacing action in which the controlling dog is shifted during such motion of said key lever.

6. In a spacing mechanism, an escapement wheel, an intermittently operable spacing wheel, slideable dogs on the spacing wheel adapted to be successively brought by the rotation of the spacing wheel into and out of the path of successive teeth of the escapement wheel and to be shifted by the teeth of the latter laterally on said spacing wheel to stop position, means for maintaining said dogs in initial position and releasing them for shifting motion to stop position and thereafter returning them to initial position, a ratchet wheel connected to the spacing wheel, a push pawl for actuating said ratchet wheel, means for actuating the push pawl, and means engageable with the pawl at the end of its feed motion for holding it in engagement with the tooth of the ratchet wheel engaged thereby.

7. In a spacing mechanism, an escapement wheel, a rotary spacing wheel rotative on an axis at right angles to the axis of the escapement wheel and provided with transverse guides in its periphery, an annular series of dogs upon the periphery of the spacing wheel arranged so as to be successively brought by intermittent motions of the spacing wheel into the path of successive teeth of the escapement wheel, said dogs being slidably mounted in said guides to be shifted by the teeth of the escapement wheel for an escape-

ment action, and means for moving the shifted dogs back to initial position.

8. In an escapement mechanism for typewriting and like machines, an escapement wheel, an intermittently operable spacing wheel mounted to rotate on an axis arranged transversely of the machine, dogs individually slideable transversely of the face of the spacing wheel into and out of the path of successive teeth of the escapement wheel so as to be shifted by the teeth of the latter laterally on said spacing wheel to stop position, a universal bar, and means actuated by said bar for imparting feed motion to the spacing wheel.

9. In an escapement mechanism for typewriting and like machines, an escapement wheel, an intermittently operable spacing wheel mounted to rotate on an axis arranged transversely of the machine, dogs individually slideable transversely of the face of the spacing wheel into and out of the path of successive teeth of the escapement wheel so as to be shifted by the teeth of the latter laterally on said spacing wheel to stop position, a universal bar, and a push pawl actuated by said bar for imparting feed motion to the spacing wheel.

10. In a spacing mechanism for typewriting and like machines, an escapement wheel, an intermittently operable spacing wheel mounted to rotate on an axis arranged transversely of the machine, dogs slideable transversely of the face of the spacing wheel and adapted to be successively brought by the rotation of the spacing wheel into and out of the path of successive teeth of the escapement wheel and to be shifted by the teeth of the latter laterally on said spacing wheel to stop position, means for maintaining said dogs in initial position and releasing them for shifting motion to stop position and thereafter returning them to initial position, a universal bar, and means actuated by said bar for imparting feed motion to the spacing wheel.

11. In a spacing mechanism for typewriting and like machines, an escapement wheel, an intermittently operable spacing wheel mounted to rotate on an axis arranged transversely of the machine, dogs slideable transversely of the face of the spacing wheel and adapted to be successively brought by the rotation of the spacing wheel into and out of the path of successive teeth of the escapement wheel and to be shifted by the teeth of the latter laterally on said spacing wheel to stop position, means for maintaining said dogs in initial position and releasing them for shifting motion to stop position and thereafter returning them to initial position, a universal bar, and a push pawl actuated by said bar for imparting feed motion to the spacing wheel.

12. In an escapement mechanism, an es-

capement wheel, a spacing wheel, dogs on the spacing wheel slidably shiftable by the teeth of the escapement wheel, and a cam device for retracting the dogs.

13. In an escapement mechanism, an escapement wheel, a channeled spacing wheel having the side walls of its channel provided with guide openings, dogs mounted in the channel of the spacing wheel for lateral movement therein in one direction by the escapement wheel, said dogs having guide members slidably engaging said guide openings, and means for sliding the dogs laterally in the opposite direction.

14. In a spacing mechanism, an escapement wheel, an intermittently operable spacing wheel, slidable dogs on the spacing wheel adapted to be successively brought by the rotation of the spacing wheel into and out of the path of successive teeth of the escapement wheel and to be shifted by the teeth of the latter laterally on said spacing wheel to stop position, means for maintaining said dogs in initial position and releasing them for shifting motion to stop position and thereafter returning them to initial position, key actuated means comprising a ratchet wheel and a pawl, the latter operative on the former in one direction of motion of the key lever for turning the spacing wheel for a spacing action in which the controlling dog is shifted during such motion of said key lever, and a stop acting at the end of the feed motion for holding the pawl in engagement with the tooth of the ratchet wheel engaged thereby.

15. In a spacing mechanism, an escapement wheel, an intermittently operable spacing wheel, slidable dogs on the spacing wheel adapted to be successively brought by the rotation of the spacing wheel into and out of the path of successive teeth of the escapement wheel and to be shifted by the teeth of the latter laterally on said spacing wheel to stop position, means for maintaining said dogs in initial position and releasing them for shifting motion to stop position and thereafter returning them to initial position, a ratchet wheel connected to the spacing wheel, a universal bar, and a push pawl actuated by the bar and movable over the teeth of the ratchet wheel in one direction of motion of said bar and engageable with the tooth of the ratchet wheel in the other direction of movement of said bar to turn the wheel for a spacing wheel feed motion.

In testimony whereof I affix my signature.
CLIFTON K. RAINES.
